(57) CLAIM

(21) Appl. No.: 29/240,202

The ornamental design for a belt having pouches for diapers or the like, as shown and described.

(22) Filed: Oct. 6, 2005

DESCRIPTION

(30) Foreign Application Priority Data

Apr. 11, 2005 (AU) 11457/2005

(51) LOC (8) Cl. 03-01

FIG. 1 is a perspective view of the belt having pouches for diapers or the like showing my new design, with the pouches shown closed;

(52) U.S. Cl. D3/224

FIG. 2 is a left side view of the invention, with the pouches closed;

(58) Field of Classification Search D3/224,

FIG. 3 is a front view of the invention with the pouches closed;

D3/226, 228; 224/901, 904, 684, 245, 240,

FIG. 4 is a rear view of the invention with the pouches closed;

224/250, 661

FIG. 5 is front view of the invention with the pouches open; and,

See application file for complete search history.

FIG. 6 is a top view of the invention with the pouches open and illustrating a pair of internal zippered pockets in one of the pouches.
